UNITED STATES PATENT OFFICE.

FELIX JOSWICH, OF ST. PAUL, MINNESOTA.

FIRE-EXTINGUISHER.

1,084,639

Specification of Letters Patent. Patented Jan. 20, 1914.

Application filed May 13, 1912. Serial No. 696,805.

To all whom it may concern:

Be it known that I, FELIX JOSWICH, a citizen of the United States, residing at St. Paul, in the county of Ramsey and State of Minnesota, have invented certain new and useful Improvements in Fire-Extinguishers, of which the following is a specification.

My invention relates to improvements in fire extinguishing apparatus, its object being particularly to provide an improved form of fire extinguishing apparatus operated through the medium of differences in pressure, as difference in pressure between the stream from the ordinary hydrant and the high pressure stream from the engine pump.

In carrying out my invention I employ a cartridge filled with soluble extinguishing material, and dissolve and force the material from the cartridge by a portion of the high pressure stream from the engine pump, the solution being forced from the cartridge into the main stream and carried with it through the pump.

To this end the invention consists in the features of construction, combination, and arrangement of parts hereinafter described and claimed.

In the accompanying drawings forming part of this specification, Figure 1 is a front elevation of an engine pump and hydrant connection showing my invention in vertical section associated therewith; and Fig. 2 is a section on line *x-x* of Fig. 1.

Referring to the drawings, A represents the pump and B the hydrant pipe leading thereto.

C represents the high pressure ejector of the pump. Arranged adjacent to the pump is the cartridge holding casing D connected at its lower end by a conduit 2 with the high pressure ejector of the pump. The upper end of the holder D is connected by an outlet side conduit 3 with the low pressure pipe

B. Adapted to be arranged within the holder B is a cartridge 4, said cartridge being filled with suitable soluble material. The cartridge 4 has an open top and is formed in its bottom with a central opening 5 through which extends a tube 6 extending upwardly from the high pressure conduit 2 to a point above the top of the cartridge. The upper end 7 of the tube is pointed and formed with surrounding perforations 8, the pointed free end of the tube allowing it to be forced through the cartridge as the

cartridge is placed upon the holder. The holder has a removable top 9 formed with a central upwardly extending closed top tube 10. Slidable in the top of the holder is a weight 11, the weight shown in the drawings being adapted to fit within the top of the cartridge and being formed with an upwardly extending closed central tube 12 to receive the pipe 6, the tube 12 extending into the tube 10 of the holder cover. The lower side of the weight 11 is preferably concaved, as shown.

Where it is desired to use the apparatus the cartridge is inserted in the holder and shoved down over the tube 6, which will cause the tube to pass through the contents of the cartridge and project above the same, as shown in the drawings. After the cartridge is in position the cover 9 may be placed back upon the holder. The apparatus is then ready for use and in use the water will pass from the high pressure ejector C through the tube 6 and perforations 8 into the top of the cartridge, dissolving the contents and carrying the same with it around the weight 11 and through the lower pressure connection 3 to the hydrant pipe B. In the hydrant pipe B the solution will mix with the main stream of water and pass through the pump in the regular manner to be used in putting out fires. The continuous flow of water in the apparatus will gradually dissolve the material in the cartridge from the top down.

I claim as my invention:

1. A fire extinguishing apparatus of the class described, comprising in combination with a high and a low pressure fluid connection, a cartridge containing soluble material, a weight slidable in said cartridge, and a stand pipe communicating with said high pressure connection and extending through said cartridge and opening above the top of the contained material, said cartridge having an outlet opening communicating with said low pressure connection.

2. A fire extinguishing apparatus of the class described, comprising in combination with a high and a low pressure fluid connection, a cartridge containing soluble material, a stand pipe communicating with said high pressure connection and extending through said cartridge, said stand pipe opening above said soluble material, and a weight slidable in said cartridge over said stand pipe, said cartridge being formed with an

dutlet vent communicating with said low pressure connection.

3. A fire extinguishing apparatus of the class described, comprising in combination with a pump and associated low pressure supply pipe and high pressure ejector, a cartridge containing soluble material, a stand pipe connected with said ejector and extending through said cartridge, said stand

pipe opening above said soluble material, 10 and an outlet conduit connecting said cartridge with said low pressure pipe.

In testimony whereof I affix my signature in presence of two witnesses.

FELIX JOSWICH.
